US00D993943S

(12) **United States Design Patent** (10) **Patent No.:** **US D993,943 S**
Kosaka et al. (45) **Date of Patent:** **** Aug. 1, 2023**

(54) **ANTENNA**

(71) Applicant: **Japan Aviation Electronics Industry, Limited**, Tokyo (JP)

(72) Inventors: **Keishi Kosaka**, Tokyo (JP); **Takeshi Ebisawa**, Tokyo (JP)

(73) Assignee: **JAPAN AVIATION ELECTRONICS INDUSTRY, LIMITED**, Tokyo (JP)

(**) Term: **15 Years**

(21) Appl. No.: **29/787,472**

(22) Filed: **Jun. 7, 2021**

(30) **Foreign Application Priority Data**

Mar. 17, 2021 (JP) ..... 2021-005405 D

(51) **LOC (14) Cl.** **14-03**

(52) **U.S. Cl.** ..... **USPC D14/230**

(58) **Field of Classification Search**

(57) **CLAIM**

The ornamental design for an antenna, as shown and described.

DESCRIPTION

FIG. 1 is a front elevational view of an antenna showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

1 Claim, 5 Drawing Sheets
